UNITED STATES PATENT OFFICE.

JOSEF SODERBERG, OF IRON MOUNTAIN, MICHIGAN, ASSIGNOR OF ONE-HALF TO ISAAC UNGER, OF IRON MOUNTAIN, MICHIGAN.

POLE-GUARD.

No. 825,683.

Specification of Letters Patent.

Patented July 10, 1906.

Application filed September 11, 1905. Serial No. 277,935.

To all whom it may concern:

Be it known that I, JOSEF SODERBERG, a citizen of the United States, residing at Iron Mountain, in the county of Dickinson and State of Michigan, have invented a new and useful Improvement in Pole-Guards, of which the following is a specification.

My present invention constitutes an improvement over the pole-guard of my Patent No. 784,902, granted March 14, 1905.

My primary object is to provide a simplified construction possessing all the advantages of the patented construction in addition to the advantages incidental to the simplification of the construction.

The invention is illustrated in the accompanying drawings, in which—

Figure 1 represents a broken perspective view of a vehicle-pole and neck-yoke equipped with my improvement; Fig. 2, a broken side elevational view with the neck-yoke removed, and Fig. 3 a plan view of the same.

In the preferred construction, A represents a pole or shaft, B a neck-yoke, and C my improved pole-guard. The guard comprises a bowed rod c, provided at its extremities with eyes joined by eyebolts c' to the end portions of the neck-yoke, and a guide member c², applied to the end portion of the pole and through which the rod is free to slide as the neck-yoke swings with relation to the pole. The member c² comprises a yoke c³, having the extremities of its arms joined by a pivot-bolt c⁴ to the pole which the yoke embraces, and a forwardly-projecting guide portion c⁵, which rests normally on the tip iron c⁶ of the pole and is in the form of a snap-hook. The extremity c⁷ of the hook is turned upwardly and points backwardly, and there is afforded a guide-channel c⁸, which is closed at its rear side by the downturned front portion of a

spring c⁹, secured to the upper surface of the body of the member c⁵. It will now be clear that the bowed rod c works freely in the guide-channel c⁸ when the device is in use 45 and that when the team is to be taken from the vehicle or when for any reason the neck-yoke is to be detached from the pole the rod may be readily disconnected from its guide by depressing the spring c⁹.

Changes in form and in minor details of construction are contemplated. Hence no undue limitation should be understood from the foregoing detailed description.

What I regard as new, and desire to secure 55 by Letters Patent, is—

1. The combination with a pole and neck-yoke, of a forwardly-bowed guard member connected with the neck-yoke, and a guide member connected with the pole having a 60 guide-channel for said guard member with a spring retaining the guard member in said channel, for the purpose set forth.

2. The combination with a pole and neck-yoke, of a forwardly-bowed guard member 65 connected with the neck-yoke, and a hook-equipped guide member pivoted on the pole and with which the guard member directly engages, for the purpose set forth.

3. The combination with a pole and neck-yoke, of a forwardly-bowed guard member connected with the neck-yoke, a member connected with the pole equipped with a hook having an upturned rearwardly-pointed extremity, and a spring co-operating with said 75 hook, substantially as and for the purpose set forth.

JOSEF SODERBERG.

In presence of—

R. T. MILLER,
ISAAC UNGER.
